WARNING TAG OR SIMILAR ARTICLE

Mary O. Byrum, Miami, Fla. (249 S. Royal Poinciana Blvd., Apt. 209, Miami Springs, Fla. 33136)

Filed Jan. 5, 1973, Ser. No. 321,298

Term of patent 14 years

Int. Cl. D20—03

U.S. Cl. D96—13

FIG. 1

FIG. 2

FIG. 3

FIG. 4

FIG. 1 is a front elevational view of a warning tag or similar article showing my new design, the rear of the tag being flat and plain;

FIG. 2 is a front elevational view of another embodiment of my new design;

FIG. 3 is a rear elevational view thereof; and

FIG. 4 is an edge view thereof.

The indicia is shown in broken lines for illustrative purposes only.

I claim:

The ornamental design for a warning tag or similar article, substantially as shown and described.
